UNITED STATES PATENT OFFICE.

JAMES H. MELICK, OF ALBANY, NEW YORK.

IMPROVEMENT IN SELF-TIGHTENING BANDS FOR HAY-FORKS.

Specification forming part of Letters Patent No. 40,701, dated November 21, 1863.

To all whom it may concern:

Be it known that I, JAMES H. MELICK, of the city and county of Albany, State of New York, have invented a new and useful Self-Tightening Band for the Tines of Hay-Forks, &c.; and I do hereby declare that the following is a full, clear, and exact description thereof, reference being had to the accompanying drawings, making a part of this specification, in which—

Figure 1 is a perspective view of my improved band, having the tooth of a pitchfork applied to it. Fig. 2 is a transverse section through a fork-head, showing the improved band applied to the same. Fig. 3 is a longitudinal section through a portion of a fork-head, showing a section through the band. Fig. 4 is a perspective view of a pitchfork having my invention applied to it.

Similar letters of reference indicate corresponding parts in the several figures.

This invention relates to a new and useful device to be applied to the wooden heads of pitchforks and other similar implements for the purpose of keeping the tines rigidly fixed in their places in the fork-head, and at the same time preventing the strain put upon the tines from splitting the head, as will be hereinafter described.

To enable others skilled in the art to make and use my invention, I will describe its construction and operation.

My invention consists in a metallic band, *a*, which is made of stout strap metal. This band, when cut of a proper length, has an oblong hole, *b*, punched in each end, and another hole, *c*, punched through it at the middle of its length. The length of this band *a* should be such as to pass around the fork-head and to allow the slotted ends to lap a short distance, as shown in Figs. 1 and 2, so that the tapering or wedged end of the shank *d* of the fork will pass through both ends of the band *a*, through a hole which is made through the fork-head, and also through the middle hole, *c*, as shown in Figs. 2 and 3, receiving on the end which has a male screw, *e*, cut on it a nut, *g*, which, on being forced up tightly, will draw the wedged shank tightly in its place, and at the same time draw the band *a* very tight around the head *A*.

In order to cause the shank of the fork to

draw the ends of the band together when the shank is forced in its place, the slots *b b* should be cut so that the narrow edges of the shank will commence to press outward on the ends of the band *a* before the shank has been drawn home, and the slots being made longer than the width of the shank the shank will only press on one edge of each slot as it is forced home, thus drawing the band tightly around the fork-head. By applying a thick metal band to the fork-shank in this way it will be seen that the wood is strengthened around the shank at the point where it would be most likely to split; also that the fork-shank has a metal bearing on each side of the head *A*, which holds the fork permanently and rigidly in position within the head.

Although I have represented in Fig. 4 my invention applied to the head of a common hay-elevating fork, I do not desire to be understood as confining its use to this or any other hay-fork exclusively, as it will be found useful in a variety of implements where it is desirable to secure teeth to a wooden head.

In using the fork for lifting heavy loads the teeth outside of the head *A* will spring back more or less in proportion to the weight put upon them. This slight spring movement of the teeth outside of the head will be resisted by that end of the band *a* which is on the opposite edge of a tooth to the edge upon which the weight is sustained, and the band will, as a consequence, be drawn more tightly on one side of the head in proportion to the weight to be sustained. The oblong slots *b b* through the ends of the band *a*, through which the tines pass, being made longer than the width of those portions of the tines outside of the head, the resile movement of these tines will only press upon and be resisted or received by one of the ends of the bands, according to whichever side of the tines the load is sustained or received on.

I am aware that the tines will retract very little, especially if they are made thick at and near their shanks; but however little this movement may be the band will be drawn more tightly about the head, and thus prevent the tines from becoming loose and rickety and losing their metal support in consequence of the shrinking of the wooden head *A*, and also resist any tendency of the rake-head to split by reason of such pressure upon the tines.

Having thus described my invention, what I claim as new, and desire to secure by Letters Patent, is—

1. So applying a band, *a*, to a rake-head, fork-head, or other like article that the strain upon the tines of the fork in the act of use shall tighten the band thereon in proportion to the strain applied upon the tines, substantially in the manner and for the purpose described.
2. The slotted band *a*, so constructed and applied to a wooden or other head that the tine

will act as a key to tighten the band upon the head, and thereby tighten the tine in the same proportion, substantially as set forth.

3. Sustaining the strain upon wooden heads or stocks of agricultural implements by means substantially as described.

JAMES H. MELICK.
